B. J. Hunter
Attorney

UNITED STATES PATENT OFFICE.

AVILA O. THOMAS, OF DETROIT, MICHIGAN.

TILE FLOOR CONSTRUCTION.

Application filed January 20, 1921. Serial No. 438,571.

To all whom it may concern:

Be it known that I, AVILA O. THOMAS, a citizen of the United States, residing at Detroit, in the county of Wayne and State 5 of Michigan, have invented a new and useful Tile Floor Construction, of which the following is a specification.

This invention relates to tile floor constructions, and more particularly to floor 10 constructions employing tiles arranged in complementary pairs to form hollow blocks.

It is one of the objects of the invention to provide a floor construction employing tiles of such form that their abutting ends 15 form a channel in which may be poured concrete or the like to form a beam.

The use of the members traversing said channel to both maintain the tiles in proper abutting relation and to transmit the weight 20 of the tiles (and the load therefrom) to said beam is another feature of the invention.

A further object is to form a hollow block of two superposed tile members having complementary engaged ribs and having portions interlocking to resist relative horizontal movement.

A preferred embodiment of the invention is hereinafter described, and is illustrated 30 in the accompanying drawing, wherein:

Fig. 1 is a vertical sectional view, showing a portion of a tile floor constructed in accordance with the invention, and showing also a portion of an exterior wall supporting 35 said floor.

Fig. 2 is an enlarged view of a portion of Fig. 1 showing how the abutting ends of the blocks provide a channel for receiving and molding a poured beam of cementitious 40 material.

Fig. 3 is a perspective view of a wedge forming a tensioning means for the tie members connecting said hollow blocks.

In these views the reference characters 45 1 and 2 designate upper and lower complementary tile members, which jointly form hollow blocks. The upper members 1 have transverse depending ribs 3 at their extremities and the lower members 2 have complementary upstanding ribs 4 set back a short distance from the ends of said members. Also abutting ribs 5 are formed upon the upper and lower members adjacent their longitudinal edges. The end portions of the 50 lower tile members 2 abutting as indicated at 6 form the bottoms of channels, the sides

of which are formed by the ribs 3 and 4, jointly. Concrete or the like is poured into said channels, forming a beam 7 to which the weight of the adjacent tiles and the load 60 thereupon is transmitted. The members 8, which support the hollow blocks upon the beams 7 function also as tie members to maintain the upper and lower tile members in proper complementary relation and to 65 insure a proper abutting relation of the adjacent lower tile members. The tie members 8 are arranged in transverse pairs, diagonally traversing the channels through the beams 7, each having at one end a head 70 9 and being engaged at its other end by suitable tensioning means. It is preferred to form the members 8 from strap iron or from sheet metal strips, each being bent at one extremity to produce the T shaped head 75 9, and having its other end portion formed with a return-bent portion 10, within which may be engaged a tensioning wedge 11.

Said tie members and their tensioning elements form the subject matter of a companion application. As shown, the heads 9 of the tie members abut against the lower tile members and the tensioning means engage the upper tile members. It is preferred to form said tile members with V- 80 shaped pockets 12 which receive the heads 85 and tensioning means of the tie members, each of said pockets having one wall transverse to the corresponding tie and apertured as indicated at 13 to give passage to said tie, 90 said walls providing suitable bearing surfaces for the heads 9 and wedges 11. Relative endwise movement of the complementary tiles of each block is prevented through 95 an interlock established between said tiles 95 by forming depending abutments 14 upon the upper tile in such position as to adapt them to engage the opposing faces of the ribs 4 of the lower tiles. Thus tensioning 100 of the tie members 8 will not disarrange the proper complementary arrangement of the tiles.

A special L-shaped tile 15 is used where a floor employing the described construction is supported by an exterior wall such as is indicated at 16, said tile being 105 arranged within said wall and co-operating with the adjacent floor blocks to form a channel within which a cement beam 17 is poured.

The described construction is substantially fire proof and affords comparatively inexpensive means for effectively trussing, 110

reinforcing and securely uniting the adjoining members of the structure. It enables a very rapid assembling of the parts and permits the beams to be poured in their positions of use integrated in the structure without the employment of temporary molds or forms as is commonly required in cement floor construction.

What I claim is:

- 10 1. In a floor construction, the combination with adjacent hollow blocks, each formed of complementary upper and lower tiles, the lower tiles having abutting ends and having transverse upstanding ribs adjacent said ends, and the upper tiles having transverse depending ribs at their ends seating upon said upstanding ribs, said upstanding and depending ribs forming the sides of a channel opening in the top surface of the floor and the abutting end portions forming 20 the bottom of said channel, one of the complementary tiles of each block having integral projections engaging said transverse ribs of the other tile to resist relative end-wise movement of the two tiles, a poured beam within said channel, and tie members diagonally traversing said channel and embedded in said beam, terminally engaging upper and lower tiles of said adjacent blocks.
- 25

bedded in said beam, terminally engaging upper and lower tiles of said adjacent blocks.

2. In a floor construction, the combination with adjacent hollow blocks, each formed of complementary upper and lower tiles, the lower tiles having abutting ends and having transverse upstanding ribs adjacent said ends, and the upper tiles having 30 transverse depending ribs at their ends seating upon said upstanding ribs, said upstanding and depending ribs forming the sides of a channel opening in the top surface of the floor and the abutting end portions forming 40 the bottom of said channel, one of the complementary tiles of each block having integral projections engaging said transverse ribs of the other tile to resist relative end-wise movement of the two tiles, a poured 45 beam within said channel, and tie members diagonally traversing said channel and embedded in said beam, terminally engaging upper and lower tiles of said adjacent blocks.

In testimony whereof I sign this specification.

AVILA O. THOMAS.
